MAILING PACKAGE

Filed Dec. 30, 1922

UNITED STATES PATENT OFFICE.

HERMAN L. GREVE, OF BROOKLYN, NEW YORK.

MAILING PACKAGE.

Application filed December 30, 1922. Serial No. 609,828.

My invention relates to merchandise which may be shipped by mail, and stocked on the shelves of the merchant in its original pack-
age.

5 The object of my invention is to provide a package of mailing wrappers which comes within the postal laws of the United States Government relating to parcels post matter, and to provide a package which comprises 10 a container holding a pre-determined number of wrappers nested together in their finished curved form, and to provide such package in a form which may be easily stocked, and from which the wrappers may be readily dispensed in one or more units without 15 handling or disturbing the remaining wrappers, or causing them to change their finished form.

Heretofore it has been the custom to ship 20 the wrappers in flat packages which soon destroyed the curved form of the wrapper and reduced to a considerable degree the advantage derived by the user in making them curved in form.

25 Further objects and advantages of my invention will be described hereinafter.

Referring to the drawings which form a part of this specification,

Fig. 1 is a perspective view of a package 30 of wrappers from which one wrapper is being removed.

Fig. 2 is a longitudinal sectional view of the container, disclosing the wrappers nested therein in their finished curved 35 form.

Fig. 3 is a cross sectional view on line 3-3 of Figure 2.

Each wrapper consists of a thin flexible sheet of paper indicated by A, which is longer and wider than the sheet of card- 40 board B, which is inclosed, and to which it is cemented, and fastening means for holding the wrapper about its contents. The card-board is flexible to a limited degree but too stiff to be easily bent about a parcel 45 to be wrapped, and therefore it is bent in the process of manufacturing, into a curved form as illustrated so that it may be easily wrapped about an article to be mailed by 50 the user.

As heretofore shipped and held in stock by the merchant in a flat package, the wrappers lost their curved form and by the present method of packing the curved form is 55 retained and the merchant may easily re-

move a single wrapper without disturbing the remainder of the package as a whole.

C, indicates a card-board container which is rectangular in cross section and slightly longer than the length of the wrappers in- 60 closed.

The container may be opened at either end and is provided with a label D, which serves to seal the flaps E—E respectively, together and to carry the data as to size and 65 quantity of wrappers contained in the package so that the merchant may be able at once to distinguish the relative sizes he has in stock and the number of each in the respective containers.

70 By reason of the container being formed rectangular in cross section, a certain amount of movement or yield of the body of wrappers may be effected in the act of removing a wrapper from the container since their 75 tendency to unfold often causes them to stick together more or less, and by exerting a little pressure in the direction of the open spaces of the container the wrappers loosen up at once and may be readily removed from 80 the nest.

Having thus described my invention I claim as new:

1. The combination of a number of flexible permanently curved-shaped mailing 85 wrappers having their curled up portions brought closer together for compactly nesting the same and their free ends in spaced relation and a mailing container providing convenient storage space therein and formed 90 rectangular in shape with end openings for allowing the removal of said wrappers in single and plurality units at one time by slight pressure of said free ends toward the interior of said container from any position 95 and without disturbing the normal curled condition of the remainder, said wrappers being held in said container against movement by the normal uncurling pressure on each other and on the longitudinal sides of 100 the container.

2. The combination of a mailing tube container suitable for shipping, storage and dispensing a number of flexible, permanent- 105 ly curved-shaped mailing wrappers having their end curled up portions brought closer together to compactly nest same in said container and held against movement by the normal uncurling pressure of the wrappers on each other and on the longitudinal sides 110

of the container, said container having end openings for allowing the removal of the wrappers either singly or in a plurality of units from said container from any position without disturbing the remainder by slight pressure of the free ends of said wrappers toward the center, said wrappers being held in said container against movement by the normal uncurling pressure on each other and on the longitudinal sides of the container.

3. The combination of a number of flexible permanently curved-shaped free mailing wrappers having their curled-up portions brought closer together for compactly nesting same and a mailing container providing convenient storage space therein and formed rectangular in shape with end openings for allowing removal of said wrappers in single and plurality units at one time as desired without disturbing the normal condition of the remainder, said wrapper held in said container against

movement by the normal uncurling pressure of the wrappers on each other and on all of the longitudinal sides of the container.

25

4. The combination of a mailing tube container suitable for shipping, storage and dispensing and a number of flexible permanently curved-shaped mailing wrappers having their end curled up portions brought closer together to compactly nest same in said container and held against movement by the normal uncurling pressure of the wrappers on each other and on a plurality of the longitudinal sides of the container, said container constructed with end openings for allowing the removal of the wrappers in any desired units at one time by a slight inward pressure toward the center of said container.

30

Signed at Brooklyn, in the county of Kings and State of New York, this 29 day of November, A. D. 1922.

HERMAN L. GREVE.
